UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

PARTY-LINE TELEPHONE SYSTEM.

1,321,319.

Specification of Letters Patent. Patented Nov. 11, 1919.

Application filed July 5, 1910. Serial No. 570,465.

To all whom it may concern:

Be it known that I, TALBOT G. MARTIN, a citizen of the United States of America, and resident of Chicago, Cook county, Illinois, have invented a certain new and useful Improvement in Party-Line Telephone Systems, of which the following is a specification.

My invention relates to telephone systems in which means are provided for enabling one subscriber on a party-line to call another subscriber on the same line. In an automatic system this has heretofore been done by a connector which is adapted to connect with the calling line, or by a special ring-back arrangement. Such a connector is equipped with a ringing connection for projecting signaling current on the party-line, thus enabling one subscriber to automatically call another on the same line. With the ring-back arrangement the reverting call does not pass through a connector, but simply goes to the automatic ringing apparatus which sends signaling current back onto the calling line, which is also, of course, the called line. These arrangements, however, are not altogether satisfactory.

My invention contemplates, therefore, a system in which one party calls another on the same line by connecting with a manual board which is equipped with a selective ringing key by which the called party on the same line is signaled after the operator answers the call.

In an automatic system in which one party calls another on the same line through a manual operator's ringing key, in the manner hereinafter explained, a considerable advantage is gained, as the apparatus is much more simple and the results are more satisfactory.

To these and other useful ends my invention consists in matters hereinafter set forth and claimed.

In the accompanying drawings Figures 1 and 2 represent central office apparatus by means of which a calling line in Fig. 1 may obtain connection with a called line in Fig. 2, and whereby an operator may signal a called party-line subscriber who is on the same line as the calling subscriber, in a system embodying the principles of my invention.

Fig. 3 is a diagrammatic representation of a portion of the central office apparatus,

illustrating the principal features of the so-called master switch E (Fig. 1).

Fig. 1 shows diagrammatically two party-line substations A and A' connected over line conductors to the individual or line switch C, which in turn has access to the first selector D. The line switch C is one of a group of line switches which is controlled by a common mechanism E usually called a master switch. This master switch controls the plungers of the group of line switches C in such a manner that they are normally held opposite the terminal of an idle trunk line leading to a selector D. The contacts of some certain level of the banks of the selector D are connected to trunk lines F which lead to an operator's position on a manual board. The remaining contacts of the banks of the selector D form terminals of trunk lines leading to second selectors H. The selector H has access through its banks to trunk lines leading to connectors, such as the connector shown at I (Fig. 2).

The substation A' and line switch C' (Fig. 2) are similar to the line switch C and substation A shown in Fig. 1. At B is shown a battery for talking and operating purposes, having its positive terminal preferably grounded at G. There may, however, be any number of batteries, depending on the conditions to be met. At R a ringing current generator is shown and at M a busy signaling machine is represented.

If a party-line subscriber, the subscriber at substation A, for example, desires to call a substation on some line other than his own, substation A', for example, he operates his calling device for the digits of the desired number, whereby a connection is set up through the line switch C, selectors D and H and connector I to the called substation. If, however, the subscriber at substation A desires to call another subscriber on his own line, he calls the digit corresponding to the bank level of the selector D, the contacts of which lead to the operator's trunks F. The operator thereupon presses a suitable key to project ringing current back upon the called line to signal the desired substation.

The automatic substations may be of any suitable or approved type. As herein represented, the substation A comprises the usual receiver 2, switch hook 3, transmitter 4, bells 5, condenser 6, and, being an automatic substation, it has the impulse springs 7 and

- 8 which are forced out of engagement by the teeth 9 on the impulse wheel 10 upon the backward rotation of said impulse wheel. The impulse wheel 10 is secured to shaft 11 to which there is also secured a dial (not shown) provided with finger holes. Allotted to the main line conductors 12 and 13, which are common to the substations A, A', etc., there is the line switch C.
- 10 The line switch C is of the same general type as disclosed in British Patent #26,301 of 1906, and also disclosed in the *American Telephone Journal* of June 6, 1908, being of a somewhat modified construction, however.
- 15 The switch consists essentially of the magnet 14 which controls the usual plunger arm 15, on the end of which is a plunger 39 (Fig. 3). The magnet 14 comprises four windings, namely, pull-in winding 16, cut-off winding 17, line winding 18 and auxiliary winding 19. The magnetic circuit of the windings 16 and 17 is separate from that of windings 18 and 19. This is due to the shape of the core. As shown, the core has 20 a flange or projection near its center to which the bracket 20^a is secured, the armatures being mounted upon the said bracket. Thus the windings 18 and 19 attract the armature 20, and windings 16 and 17 attract 25 only armature 21 and plunger arm 15. The winding 16, when energized, is of sufficient strength to pull up both the armature 21 and plunger arm 15, while the winding 17 is only of sufficient strength to pull up the 30 armature 21, but will hold the plunger arm 15 in an operated position after it has been pulled up by the winding 16. When the plunger arm 15 is attracted the plunger 39 (Fig. 3) is forced into a bank of springs 35 and forces the springs 22, 23, 24 and 25 into engagement with the springs 26, 27, 28 and 29, respectively. There is only one set of these springs (22-29) shown, but there may be a number of such sets in the bank 40 to which the plunger of the line switch C. has access, each set containing terminals of trunk lines leading to selectors similar to the selector D, and each set is connected in multiple with the corresponding sets in the 45 banks of all the other line switches of the group of which the switch C is a member.
- The master switch E (Fig. 3) is of the same general type as is disclosed in the British patent hereinabove referred to, and 50 more particularly that shown in said *American Telephone Journal* of June 6, 1908, but, like the line switch, is modified in construction. It comprises the ratchet wheel 30, motor magnet 31 for operating said wheel, 55 relays 32 and 33, and the locking plate 34 near the outer edge of which are openings 35, which openings may be engaged by the pin 36 on the arm 37. The plate 34 is secured to the shaft 38 (Fig. 3), which is connected 60 with the plunger shaft 38^a, with which the
- plungers are normally in engagement. The openings in the locking plate 34 can be engaged by the pin 36 only when the said plungers 39 are directly opposite the terminals of a trunk line leading to a selector 70 D. The master switch also comprises a bank *a* consisting of individual segments *b* and a common segment 40. Some one of the individual segments *b* (there being one for each trunk line leading to selector E) is kept in 75 electrical connection with the common segment 40 by means of the wiper 41. The rotary motion of the ratchet wheel 30 is transmitted to the plunger shaft 38^a by means of link 30^a and shaft 38, thereby giving said 80 plunger shaft an oscillatory motion to carry the plungers back and forth in front of the trunk terminals.
- The selector switch D is of the general type disclosed in United States Letters Patent #815,321, granted March 13, 1906, to Keith, Erickson and Erickson, but is slightly modified to operate in conjunction with a two-wire system. It comprises the usual shaft (not shown) carrying the wipers 90 42, 43 and 44. This shaft has a vertical motion controlled by the vertical magnet 45 and a rotary motion controlled by the rotary magnet 46. The selector is also provided with the slow acting relays 47, 48 and 49 (by 95 "slow acting" I mean relays that are slow to deenergize after their energizing circuits are broken), double-wound relay 50, release magnet 51 which is supplied with battery current only when the shaft is raised one or 100 more steps, thereby lifting the arm 52 and permitting spring 53 to engage spring 54, and private magnet 55. The private magnet 55 controls the usual side switch carrying the wipers 56, 57, 58 and 59.
- The trunks F leading to the operator's position are each supplied with a double-wound relay 60, lamps 61 and 62, relay 63, master key K and ringing keys K', K², K³, etc. By means of the keys K', K², K³, etc., 105 ringing current of different frequencies may be connected with the trunk line.
- The operator's talking set is shown at S.
- The selector II, Fig. 4, is similar to the selector D.
- The connector I, Fig. 2, is of the general type disclosed in United States Letters Patent #815,176, granted March 13, 1906, to Keith, Erickson and Erickson, being modified, however, to operate in a two-wire system. The connector, like the selectors, is provided with a double-wound relay 64, vertical magnet 65 and rotary magnet 66 for controlling the wipers 67, 68 and 69, a release magnet 70, slow relays 71 and 72, and private magnet 73 which controls the side switch wipers 74, 75, 76, 77 and 141. In addition, the connector is supplied with a ringing relay 78, back-bridge relay 79 through which the called subscriber receives 110 120 125 130

talking battery current, and a busy locking relay 80. The line switch C and substation A² are similar to line switch C and substation A of Fig. 1.

5 A clearer understanding of my invention may be had by considering its operations when one subscriber calls another. First I will explain how the subscriber at substation A, for example, calls another subscriber, the one at substation A², for example, whose number we will assume to be 2220. Next I will explain the operations of the central office mechanism when a party-line subscriber calls another subscriber on the same 10 line—that is, when subscriber at substation A calls the subscriber at substation A', for instance.

When the subscriber at substation A removes the receiver 2 preliminary to making 20 a call, an energizing circuit is closed through the line winding 19 of the line switch C. This circuit extends from ground G' through the springs 81 and 82, line conductor 13, substation springs 83 and 84, impulse springs 7 25 and 8, transmitter 4, line conductor 12, springs 86 and 87 and line winding 19 to the battery lead 89, thence through battery B to ground G. The armature 20, upon pulling up, shifts the spring 90 into engagement 30 with the spring 81, whereby a circuit is completed through the pull-in winding 16 in series with the auxiliary winding 18. This circuit extends from ground G' through the springs 81 and 90 and windings 16 and 18 35 to the battery lead 89. The pull-in winding 16, upon energizing, attracts both the armature 21 and the plunger arm 15. The armature 21 operates to open the circuit of the line winding 19 by separating the springs 82 40 and 86 from the springs 81 and 87, respectively, and also by shifting the spring 86 into engagement with spring 88 closes the line 12 onto the normal conductor 91, which, however, is functionless at this time. The 45 pulling up of the plunger arm 15 operates as before stated to close the springs 22, 23, 24 and 25 into engagement with springs 26, 27, 28 and 29. The closure of springs 22 and 23 with springs 26 and 29, respectively, closes 50 the circuit of the double-wound line relay 50 of the selector D. This circuit extends from ground G² through the lower winding of relay 50, side switch wiper 56, bank springs 29 and 25, line conductor 13, through substation A, as previously traced, back over line 12, springs 22 and 26, wiper 57 and upper winding of relay 50 to battery. The relay 50 energizes over this circuit to close a circuit through the slow relay 49 extending 55 from ground G³ through springs 93 and 94 and slow relay 49 to battery. The relay 49, upon energizing, shifts spring 95 out of engagement with spring 96 and into engagement with spring 97, and also forces spring 60 98 into engagement with spring 99. The

closing of springs 98 and 99 closes a circuit through the winding 17 of the line switch C, and also extends a guarding potential over conductor 195 to the private bank contact of the calling line in the banks of all of the 70 connectors that have access to said line. The circuit through the winding 17 extends from ground G⁴ through springs 98 and 99, thence over conductor 100, through springs 27 and 23 and winding 17 to battery. This 75 circuit is closed through the winding 17 before the armature 20 has had time to fall back upon the breaking of the circuits of the winding 19 at the springs 81 and 87. The armature 20 is held in an operated position for a moment after the circuit of the winding 19 is broken, due to the fact that current is flowing through the winding 18. When the plunger arm reaches its operated position, the winding 18 is short-circuited, 85 thereby causing it to deenergize slowly and consequently hold the armature 20 in an operated position a sufficient length of time to allow the circuit to be closed through the winding 17, as previously traced. This energizing circuit through the winding 17 serves to hold the plunger arm 15 and armature 21 in an operated position. The closure of the bank springs 24 and 28 closes an 90 energizing circuit through the relay 32 of the master switch. Assuming that the trunk picked by the plunger was the first trunk, the master switch wiper will be on the contact 103; hence the circuit through the relay 32 extends from ground G⁵ through the 100 springs 24 and 28, contact 103, wiper 41, common segment 40 and relay 32 to battery. The relay 32, upon energizing, closes the 105 circuit of the relay 33, which in turn pulls up the armature 37. The armature 37, in pulling up, lifts the pin 36 from the opening 35 in the plate 34, disconnects battery from the pull-in windings of the remaining idle line switches of the group of which the switch C is a member by disconnecting the 110 armature 37 from the spring 104, and by closing the springs 104 and 105 connects the busy signaling machine M' with the winding 18. This prevents any line switch from being operated while its master switch is operating. Any subscriber attempting to call at this time will receive the busy signal from the machine M', due to the inductive 115 relation between the windings 18 and 19 of the switch C. The pulling up of the armature 37 also closes the circuit through the motor magnet 31. This circuit extends from ground G⁶ through the motor magnet 31, interrupter springs 106, contact 107 and armature 37 to battery. The interrupter 120 springs 106 being included in the motor magnet circuit allows it to operate in the manner of a buzzer to rotate the ratchet wheel 30, and consequently to move the plungers from in front of the first trunk. 125

As soon as the shaft is moved a short distance the hole in the plate 34 which was engaged by the pin 36 passes from under the pin. The pin 36 then rides on the plate 34 and continues to hold the circuit of the magnet 21 closed after the wiper 41 passes off the contact 103 and until the pin 36 engages the next opening, at which time the plungers will, as hereinbefore stated, be directly opposite the terminals of the next trunk. Should the next trunk be busy the relay 32, which deenergized as soon as the wiper 41 passed off the contact 103, will again be energized and the pin 36 will not be permitted 10 to engage the next opening, and consequently the plungers will be moved to the next trunk, and so on until the wiper 41 strikes a non-grounded contact.

The foregoing operations take place upon 20 the removal of the receiver at the calling substation. The subscriber at substation A now operates the calling device for the first digit 2. The circuit of the relay 50 is broken twice at the impulse springs 7 and 8. 25 The relay 50 momentarily deenergizes twice and completes a circuit through the vertical magnet 45. The relay 49 being slow acting does not deenergize during the momentary interruption of its circuit at springs 93 and 30 94; therefore the circuit through the vertical magnet 45 extends from ground G^3 through springs 93 and 92, springs 95 and 97, slow relay 48, vertical magnet 45 and side switch wiper 59 to battery lead 89. The vertical 35 magnet energizes twice to raise the shaft and shaft wipers two steps to a point opposite the second level of bank contacts which are terminals of trunks leading to the selector H. The relay 48, which is energized as soon 40 as the first impulse is sent through it, being slow, remains in an energized position until a moment after the last impulse is delivered. In its energized position it closes the circuit of the private magnet 55. This circuit extends 45 from ground G^3 through springs 108 and 109 and private magnet 55 to battery. The relay 48, upon deenergizing, breaks the circuit just traced and allows the private magnet to deenergize, which in turn allows 50 the side switch to pass to second position in the usual manner. The passing of the wiper 59 to second position shifts the battery connection from the vertical magnet 45 to the rotary magnet 46. A circuit is 55 then completed through the rotary magnet extending from ground G^2 through the interrupter springs 110, rotary magnet 46, relay 47 and side switch wiper 59 to battery. The rotary magnet operates to rotate the 60 shaft wipers one step onto the contacts of the first trunk line leading to a selector H, and also presses down the private magnet armature and breaks its own circuit at the interrupter springs 110. Upon breaking its 65 own circuit it allows its armature to fall

back, and if the first trunk is idle the private magnet armature will also fall back and allow the side switch to pass to third position. If, however, the first trunk is busy the private magnet armature will be held up by 70 a circuit through the private magnet, said circuit extending from ground G^7 through the selector H belonging to the busy trunk to the first private bank contact in the second level of the selector D, thence through the 75 private wiper 43, side switch wiper 58 (in second position) and private magnet 55 to battery. The private magnet thus locks the side switch in second position and the rotary magnet is again energized to rotate the shaft 80 wipers onto the second contact. These operations are repeated until the private wiper strikes a non-grounded contact, at which time the side switch passes to the third position. The passing of the wipers 56 and 57 85 to the third position completes a circuit through the double-wound relay 111 of the second selector H in the same manner as the circuit was completed through the relay 50 of the selector D. The relay 111 pulls up and closes a circuit through the relay 115. The relay 115, upon energizing, puts a holding circuit back over the release trunk 119 to the relay 49 of the selector D, and also puts a guarding ground on the private banks 90 of all the first selectors that have access to the selector H. This guarding ground extends from ground G^7 through the side switch wiper 116, springs 117 and 118 and conductor 119 to the said private contacts. The circuit through the slow relay 49 extends from this ground at the private bank contact through the private wiper 43, side switch wiper 58, springs 120 and 121 and relay 49 to battery. Thus the relay 49 remains energized after the relay 50 has deenergized. A short period of time elapses between the time that the wipers of the selector D pass to third position and the time that the relay 115 pulls up to place a 110 guarding ground back, as explained, during which time ground is supplied to the private bank contact from ground G^8 . It will be remembered that the relay 47 was in the circuit with the rotary magnet and was energized by the first impulse, but being slow does not deenergize until a moment after the side switch has passed to third position; therefore a circuit extends from ground G^8 through springs 122 and 120, wiper 58 to 120 private wiper 43, thence to the private bank contacts above mentioned. The relay 47 must be quicker than the relay 49, however, in order to permit the springs 120 and 121 to close the circuit of relay 49 before it deenergizes. 115

The subscriber at substation A now operates the calling device for the second digit 2. The operations of the selector H are the same as were those of the selector D, 125 180

Briefly, the operations of the selector H are as follows: The calling device opens the line twice, thereby breaking the circuit of the relay 111 twice. The relay 111 deenergizes 5 to twice close the circuit through the relay 112 and vertical magnet 113. These operate, as described, for the selector D to raise the shaft and shaft wipers two steps, and to also energize and deenergize the private 10 magnet 114, which in turn permits the side switch to pass to second position. When the side switch is in second position the rotary magnet operates to rotate the shaft onto an idle trunk line leading to a connector I, and 15 the private magnet again operates to permit the side switch to pass to the third position, whereby a circuit is closed through the relay 64 of the connector. This circuit extends from ground G¹ through lower winding of relay 64, conductor 123, wiper 124, side switch wiper 125, conductor 126, wiper 44 (which would be standing on contact 127), thence over the heavy conductor to and 20 through substation A, back over the heavy conductor, wiper 42, bank contact 128, conductor 129, wiper 130, shaft wiper 131, conductor 132 and upper winding of relay 64 to battery. The relay 64 energizes to close the circuit of the relay 72 in the same manner as the circuits were closed through the 25 relays 115 and 49 of the selectors. The relay 72, upon energizing, performs the same functions as did relay 115—that is, puts guarding and holding ground back over the release trunk 133 and also opens the circuit 30 of the release magnet 70. The calling subscriber now operates the substation calling device for the third digit 2, thereby opening the circuit of the connector line relay 64 twice. Each time the relay 64 deenergizes a 35 circuit is closed extending from ground G¹⁰ through springs 134 and 136, 137 and 138, vertical magnet 65, side switch wiper 141 and private magnet relay 71 to battery. The 40 vertical magnet operates in response to these impulses to raise the shaft and wipers 67, 68 and 69 two steps to a point opposite the second row of level of bank contacts. The 45 private magnet relay 71 operates, as in the case of the selectors D and H, to close the circuit of the private magnet 73 while the vertical magnet is operating. After the last impulse is delivered to the vertical magnet, the relay 71 breaks the circuit of private 50 magnet 73, which in turn deenergizes and permits the side switch to pass to second position. The subscriber now operates the calling device for the last digit 0. The relay 64 deenergizes ten times and completes the 55 circuit through the rotary magnet 66. This circuit extends from ground G¹⁰ through springs 134 and 136, 137 and 138, 139 and 140, rotary magnet 66, side switch wiper 141 and slow relay 71 to battery. The rotary 60 magnet energizes ten times to rotate the 65 magnet wipers onto the contacts of the called line. The relay 71, upon energizing, closes the circuit of the private magnet 73. The relay 71 deenergizes a moment after the last impulse has been delivered, whereupon, if the 70 called line is idle, the private magnet 73 deenergizes and allows the side switch wipers to pass to third position. The wiper 74, in passing to third position, shifts the holding ground for the relay 115 of selector 75 H from ground G¹¹ to ground G¹⁰. The wiper 77, in passing to third position, puts ground onto the private bank contact of the called line in the banks of all of the connectors that have access to the lines of the 80 called subscriber. This circuit extends from ground G¹² through side switch wiper 77, springs 142 and 143, private wiper 68, and thence to the private bank contacts. A circuit also extends from this ground at the 85 private wiper 68 over conductor 144 and through winding 145 to battery. The winding 145, upon energizing, attracts the armature 146, which operates to disengage the line winding 147 and ground G²⁰ from the 90 lines of substation A², and to extend the conductor 151 to the line conductor 164 through springs 152 and 148. The wipers 75 and 76, upon passing to 95 third position, complete the connection from the calling substation A to the substation A² through condensers 153 and 154. When the wiper 141 passes to third position, battery is shifted from the rotary magnet to the ringer relay 78. The ringer relay now 100 energizes over a circuit extending from ground G¹³ through interrupter 155, springs 156 and 157, relay 78, wiper 141 and relay 71 to battery. The relay 78 thus intermittently energizes through the medium of 105 the interrupter 155 to place ringing current on the line of substation A². This ringing current flows over a circuit extending from one side of generator R through springs 158 and 159, wipers 76 and 67, 110 springs 152 and 148, line 164, bells 165, condenser 166, springs 167 and 168, line 169, wipers 69 and 75 and springs 162 and 161 to the other side of generator R. The subscriber at substation A², upon hearing the 115 signal, removes the receiver from the hook, and as soon as the ringing relay again deenergizes a circuit is completed extending from ground G¹² through lower winding of relay 79, ringer springs 163 and 162, wipers 120 75 and 69, line 169, springs 168 and 170, thence through the impulse springs receiver and transmitter at the substation A², back over line 164, springs 148 and 152, wipers 67 and 76, springs 159 and 160 and upper 125 winding of relay 79 to battery. This circuit supplies the called subscriber with talking battery current. The relay 79, upon energizing, opens the ringer relay circuit at the springs 156 and 157. The calling 130

subscriber receives his talking battery current through the relay 64. The subscribers may now carry on a conversation.

The release of the apparatus used in the connection is brought about by the replacing of the receiver on the hook at the calling substation. The hanging up of the receiver at this substation opens the circuit of the relay 64 of the connector I at the 10 springs 83 and 84, whereupon the relay 64 falls back and, by so doing, opens the circuit of the release relays 72, 115 and 49 of the connector I and the selectors H and D, respectively. The relay 72, upon falling 15 back, closes a circuit through the release magnet 70 of the connector. This circuit extends from ground G^{10} through the springs 134 and 136, springs 137 and 170, magnet 70 and off normal springs 172 and 20 171 to battery. The switch is thereby released and the shaft, upon reaching its lowest position, separates the springs 171 and 172 to break the release magnet circuit. The relays 115 and 49, upon falling back, 25 close circuits through their respective release magnets similar to the one traced for the connector. When the relay 49 deenergizes it also opens the holding circuit of the winding 17 of the line switch C. The winding 17 deenergizes and allows the plunger to return to normal position. Thus the switches are all put in readiness for another call.

If the called line had been busy the private magnet 73 of the connector would not have deenergized when the relay 71 deenergized after the last digit was called, but would have remained energized over a circuit extending from the ground which 30 would have been on the private bank contact of the busy line, through the private wiper 68, springs 143 and 142, lower winding of relay 79, ringer springs 163 and 162, wiper 75 (in second position), springs 173 35 and 174 and private magnet 73 to battery. As the relay 71 deenergizes, the spring 174 engages spring 173 before it disengages spring 176, so that the relay 73 remains energized after relay 71 deenergizes, and at 40 the same time relay 79 is energized. The simultaneous energization of relay 79 and private magnet 73 closes a circuit through the relay 80 extending from ground G^{14} through springs 176 and 175, springs 177 45 and 178, relay 80 and springs 179 and 180 to battery. The relay 80, upon energizing, opens the operating circuit of the rotary magnet, shifts the holding ground for the relay 79 and magnet 73 from the ground at 50 the private bank contact to ground G^{15} , and also puts a busy signal on the line of the calling subscriber. This busy signal circuit extends from battery through the secondary of the induction coil 181, through springs 55 182 and 183, wiper 76, ringer springs 160

and 161, condenser 153, thence over the circuit previously traced, through substation A, and back through the lower winding of relay 64 to ground, thence through battery to the starting point. The calling subscriber, upon hearing the busy signal, replaces the receiver on the hook. The act of replacing the receiver on the hook releases the switches in the manner hereinabove described. 75

The foregoing is a description of how one subscriber can call another subscriber on a different line. In this description it will be remembered that the calling line is provided with a guarding potential at its 80 connector private bank contacts as soon as the line switch C operates. If now a party line subscriber should attempt to call some other subscriber on his own line through the selectors D and H and connector I, the 85 guarding potential at the connector private bank contacts would prevent the connector from completing the connection. Therefore I have provided the operator's trunk circuit F, by means of which an operator may 90 project ringing current back over a calling party line to signal any desired substation thereon. When a party line subscriber wishes to communicate with some other subscriber on his own line, he removes his receiver and operates his calling device for the digit corresponding to the bank level of the selector D to which the trunks F are connected. Since in this instance the trunks F are assumed to be connected with the 100 tenth or 0 level of the selectors, the calling subscriber operates his calling device for the digit 0. The selector D operates in response to the impulses for this digit in the same manner as explained for the first digit of 105 the number 2220, except that its wipers are raised ten steps instead of two. Thus the wipers are raised ten steps and then automatically rotated onto an idle trunk F leading to the manual board. As soon as the 110 wipers of the selector pass to the third position a circuit is closed through the double-wound relay 60. This circuit extends from ground G^{16} through the lower winding of relay 60 to the heavy conductor, thence over 115 the heavy conductors, as previously traced, to and through substation A, back over the heavy conductors and through the upper winding of relay 60 to battery. The relay 60 pulls up and extends a holding and 120 guarding ground back over the release trunk from ground G^{17} through springs 184 and 185. It also closes a circuit through the supervisory lamp 61. This circuit extends from ground G^{18} through springs 186 and 125 187, springs 188 and 189 and lamp 61 to battery. The lamp is lighted and signifies to the operator that she is wanted. The operator, upon observing the signal, closes the key K, whereby the talking set S is con- 130

connected to the line and a circuit is also closed through the relay 63. This circuit extends from ground G¹⁶ through springs 190 and 191 and relay 63 to battery. The relay 63, upon energizing, opens the circuit of lamp 61 and closes the circuit of lamp 62 and also puts a new holding ground onto the release trunk. This circuit extends from ground G¹⁶ through the springs 190 and 191, springs 194 and 193 to the private wiper 43, thence through the relay 49 previously described. Upon learning that the substation A' is desired the operator requests the calling subscriber to hang up his receiver. The switches 15 C and D do not release because of the holding ground G¹⁶. The operator then closes a ringing key K', for example, which puts a ringing current of the proper frequency out on the line to operate the bells at the substation A'. After a moment the party at the substation A removes the receiver and waits until the party at substation A' answers. The two parties may then converse, receiving talking battery current through 25 the relay 60. Upon hearing the called party answer, the operator again opens the key K, thereby disconnecting her set from the line. After the key K is restored the relay 63 remains energized over a circuit extending from ground G¹⁷ through the springs 184 and 185, 193 and 194 and relay 63 to battery. Thus, while the two subscribers are conversing the lamp 62 continues to glow, while the circuit of the lamp 61 is opened. 30 35 After both receivers are hung up upon the termination of the conversation, the relay 60 deenergizes, breaking the circuit of the relay 63 and of the relay 49 of the selector D. The relay 63, upon deenergizing, breaks the circuit of the lamp 62 to signify that both subscribers have hung up. The relay 49, upon deenergizing, allows the selector D and line switch C to be restored to normal position in the manner previously explained. 40 45 From the foregoing it will be seen that I provide a simple and highly efficient arrangement for enabling one party to call another on the same line. It requires the services of an operator, but for this particular purpose I find that this is more satisfactory than the use of automatic apparatus for ringing a called party on the calling line.

What I claim as my invention is:

1. In a telephone system, a party-line, an operator's selective ringing key apparatus, means including a switch controlled by the calling subscriber for connecting the party-line with said apparatus when one party calls another on the same line, means 55 normally operative to release said switch when the subscriber replaces his receiver on the hook, and means for preventing this release when a party establishes connection with said selective ringing key apparatus.
- 60 65 2. In a telephone system, a party-line, an

operator's ringing key mechanism, means including an automatic switch for connecting said party-line with said mechanism when one party calls another on the same line, means controlled by a subscriber on said 70 party-line, for releasing said switch, and means controlled by said operator's mechanism for preventing said release.

3. In a telephone system, a party-line, a selective ringing key apparatus, a trunk leading to said apparatus, a selector in which said trunk has a bank terminal, means including a switch controlled by said party-line for connecting said party-line with said selector, means for controlling said selector 80 to connect the party-line with said trunk to enable one party to call another on the same line, and a battery for supplying talking current connected in bridge of said trunk line.

4. In a telephone system, a party-line, an operator's ringing key mechanism, means including an automatic switch for connecting said line with said mechanism only when one party calls another on the same line, a signal responsive when the operator is called, a signal to indicate that a disconnection is desired, means for releasing said automatic switch, and means controlled by said operator for preventing said release.

5. In a telephone system, a party-line, an operator's selective ringing key apparatus, means including a switch controlled by the calling subscriber for connecting the party-line with said apparatus only when one party calls another on the same line, a manual board for said ringing key, and a common source of operating and talking current connected in bridge of the line by the establishment of connection to said board.

6. In a telephone system, a party-line, an operator's ringing key mechanism, means including an automatic switch for connecting said party-line with said mechanism only when one party calls another on the same line, a manual board for said ringing key, and a common source of operating and talking current connected in bridge of the line by the establishment of connection to said board.

7. In a telephone system, a party-line, a selecting ringing key apparatus, a trunk leading to said apparatus, a selector in which said trunk has a bank terminal, means for connecting said party-line with said selector, means for controlling said selector to connect the party-line with said trunk only when one party calls another on the same line, a manual board for said ringing apparatus, and a common source of operating and talking current connected in bridge of the line by the establishment of connection to said board.

8. In a telephone system, a party-line, an operator's ringing key mechanism, means

including an automatic switch for connecting said line with said mechanism only when one party calls another on the same line, a signal responsive when the operator is called, a signal to indicate that a disconnection is desired, a manual board for said ringing key, and a common source of operating and talking current connected in bridge of the line by the establishment of connection to said board.

9. In a telephone system, a party-line, an operator's selective ringing key apparatus, means including a switch controlled by the calling subscriber for connecting the party-line with said apparatus only when one party calls another on the same line, and means at each station on said line for controlling the two sides of the latter in series to effect connection to the location of the ringing key apparatus.

10. In a telephone system, a party-line, an operator's ringing key mechanism, means including an automatic switch for connecting said party-line with said mechanism only when one party calls another on the same line, and means at each station on said line for controlling the two sides of the latter in series to effect connection to the location of the ringing key.

11. In a telephone system, a party-line, a selective ringing key apparatus, a trunk leading to said apparatus, a selector in which said trunk has a bank terminal, means for connecting said party-line with said selector, means for controlling said selector to connect the party-line with said trunk only when one party calls another on the same line, and means at each station on said line for controlling the two sides of the latter in series to effect connection to the location of the ringing key.

12. In a telephone system, a party-line, an operator's ringing key mechanism, means including an automatic switch for connecting said line with said mechanism only when one party calls another on the same line, a signal responsive when the operator is called, a signal to indicate that a disconnection is desired, and means at each station on said line for controlling the two sides of the latter in series to effect connection to the location of the ringing key.

13. In a telephone system, a party-line, an operator's selective ringing key apparatus, and means including a switch controlled by the calling subscriber for connecting the party-line with said apparatus when one party calls another on the same line, said party-line being provided with a non-numerical trunking switch individual thereto for extending the initial connection therefrom, responsive to the calling subscriber.

14. In a telephone system, a party-line, an operator's ringing key mechanism, and means including an automatic switch for

connecting said party-line with said mechanism when one party calls another on the same line, said party-line being provided with a non-numerical trunking switch individual thereto for extending the initial connection therefrom, responsive to the calling subscriber.

15. In a telephone system, an operator's ringing key mechanism, a party-line, and means comprising a first selector for connecting the party-line with said mechanism when one party calls another on the same line, said party-line being provided with a non-numerical trunking switch for extending the initial connection therefrom, responsive to the calling subscriber, a plurality of magnets for controlling said switches, and means controlled by said mechanism for signaling a subscriber on said party line over a path excluding all of said magnets.

16. In a telephone system, a party-line, a selective ringing key apparatus, a trunk leading to said apparatus, a selector in which said trunk has a bank terminal, a non-numerical trunking switch responsive to the calling subscriber for connecting said party-line with said selector, and means for controlling said selector to connect the party-line with said trunk when one party calls another on the same line, a plurality of magnets for controlling said switches, and means controlled by said mechanism for signaling a subscriber on said party line over a path excluding all of said magnets.

17. In a telephone system, a party-line, an operator's ringing key mechanism, means including an automatic switch for connecting said line with said mechanism when one party calls another on the same line, a signal responsive when the operator is called, and a signal to indicate that a disconnection is desired, said party-line being provided with a non-numerical trunking switch individual thereto for extending the initial connection therefrom, responsive to the calling subscriber.

18. In a telephone system, a party-line, an automatic switch, an operator's ringing key mechanism, trunk lines extending to said mechanism, means for controlling said switch for selecting one of said trunks, means controlled by said ringing key mechanism for supplying ringing current back over said selected trunk line to said party-line, means controlled by a subscriber on said party-line for releasing said switch, and means controlled by said operator's mechanism for preventing said release.

19. In a telephone system, a party-line, an automatic switch having a plurality of contact levels, an operator's key mechanism, trunk lines extending to said mechanism from one or more of said contact levels, means for controlling said switch to select one of said trunks, means controlled by said

ringing key mechanism for supplying ringing current back over said selected trunk line to said party-line, means normally operative to release said switch when the subscriber replaces his receiver on the hook, and means for preventing this release when a party establishes connection with said selective ringing key apparatus.

20. In a telephone system, a party-line, an automatic switch, an operator's ringing key mechanism, trunk lines extending to said mechanism, means for controlling said switch over two sides of the line circuit in series for selecting one of said trunks, magnets for controlling said switch, and means controlled by said ringing key mechanism for supplying ringing current back over said selected trunk line to said party-line over a path excluding all of said magnets.

21. In a telephone system, a party-line, an automatic switch having a plurality of contact levels, an operator's key mechanism, trunk lines extending to said mechanism from one or more of said contact levels, means for controlling said switch over two sides of the line circuit in series to control the equipment thereof in one plane to select levels and in another plane to select one of said trunks, and means controlled by said ringing key mechanism for supplying ringing current back over said selected trunk line to said party-line.

22. In a telephone system, a party-line, an operator's ringing key mechanism, means including an automatic switch for connecting said line with said mechanism when one party calls another on the same line, a signal, means for operating said signal when an operator is called, means for rendering said signal inoperative when said operator answers, a second signal operated thereafter during the connection, means for releasing said automatic switch, and means controlled by said operator for preventing said release.

23. In a telephone system, a party-line, an automatic switch, an operator's ringing key mechanism, trunk lines extending to said mechanism, means for controlling said switch for selecting one of said trunks, means controlled by said ringing key mechanism for supplying ringing current back over said selected trunk line to said party-line, a signal at said operator's position for indicating when an operator is called, a second signal for indicating when a trunk is occupied, means for releasing said automatic switch, and means controlled by said operator for preventing said release.

24. In a telephone system, a party-line, an automatic switch having a plurality of contact levels, an operator's key mechanism, trunk lines extending to said mechanism from one or more of said contact levels, means for controlling said switch to select one of said trunks, means controlled by said

ringing key mechanism for supplying ringing current back over said selected trunk line to said party-line, a signal at said operator's position for indicating when an operator is called, a second signal for indicating when a trunk is occupied, means for releasing said automatic switch, and means controlled by said operator for preventing said release.

25. In a telephone system, a party-line, an automatic switch, an operator's ringing key mechanism, trunk lines extending to said mechanism, means for controlling said switch over two sides of the line circuit in series for selecting one of said trunks, means controlled by said ringing key mechanism for supplying ringing current back over said selected trunk line to said party-line, a signal at said operator's position for indicating when an operator is called, and a second signal for indicating when the trunk is occupied, and means controlled by the calling subscriber on said party line for releasing said switch.

26. In a telephone system, a party-line, an automatic switch having a plurality of contact levels, an operator's key mechanism, trunk lines extending to said mechanism from one or more of said contact levels, means for controlling said switch over two sides of the line circuit in series to first select one of said levels and to thereafter select one of said trunks, means controlled by said ringing key mechanism for supplying ringing current back over said selected trunk line to said party-line, a signal at said operator's position for indicating when an operator is called, and a second signal for indicating when the trunk is occupied.

27. In a telephone system, a party line, a ring-back apparatus for enabling one party to call another on the same line, means including a first selector having vertical and rotary motion for connecting the line with the said apparatus, and means for supplying currents of different frequencies, said ring-back apparatus provided with means controlled by an operator for selecting the proper current for signaling a party on said line.

28. In a telephone system, a party line, a ring-back apparatus for selectively signaling thereon, means for supplying ringing currents of different frequencies, a first selector for extending connection to said apparatus, means for extending connection from said line to said first selector, a plurality of magnets for controlling the extension of said connection, said ring-back apparatus provided with means controlled by an operator for selecting the proper frequency for signaling substations on said line, and for applying said signaling current to said line over a path excluding all of said magnets.

29. In a telephone system, a party line,

- means for automatically extending connection from said line including a ring-back apparatus for enabling one party to call another on the same line, means for connecting the line with the said apparatus, a plurality of magnets for controlling said connecting means, and means for supplying different kinds of ringing current, said ring-back apparatus provided with means controlled by an operator for selecting the proper current for signaling a party on said line, and for applying said signaling current to said line over a path excluding all of said magnets. 5
30. In a telephone system, a plurality of party lines and trunk lines divided into groups, a ring-back apparatus for enabling one party to call another on the same line, a first selector having motion in one plane to select groups of trunks and motion in an intersecting plane to find a trunk in a selected group for connecting the line with the said apparatus, and means for supplying currents of different frequencies, said ring-back apparatus provided with means controlled by an operator for selecting the proper frequency for signaling a party on said line. 10
31. In a telephone system, a line, a substation and a signal in bridge of said line, a trunk line extending to an operator's position, means including an automatic switch controllable by the subscriber at said station for connecting with said trunk line, a ringing key apparatus for connecting said trunk with a source of ringing current to operate said signal, means normally operative to release said switch when the subscriber replaces his receiver on the hook, and means whereby the operator can prevent such release after connection has been established with said trunk line. 15
32. In a telephone system, a party line and a plurality of subscribers' stations in bridge thereof, a trunk line extending to an operator's position, means including an automatic switch controlled by a calling subscriber on said party line for connecting with said trunk line, ringing equipment associated with said trunk line for selectively signaling subscribers on said party line, means normally operative to release said switch when the subscriber replaces his receiver on the hook, and means whereby the operator can prevent such release after connection has been established with said trunk line. 20
33. In a telephone system, a plurality of party lines, a plurality of subscribers' stations in bridge of each line, a trunk line extending to an operator's position, automatic switches accessible to calling lines, each switch when seized by a calling line controllable over the two sides of such calling line in series for connecting with said trunk line, ringing equipment associated with said trunk line for selectively signaling subscribers on said party line, means normally operative to release said switch when the subscriber replaces his receiver on the hook, and means whereby the operator can prevent such release after connection has been established with said trunk line. 25
34. In a telephone system, a line, a substation and a signal in bridge of said line, a trunk line extending to an operator's position, means including an automatic switch controllable by the subscriber at said substation for connecting with said trunk line, a ringing key apparatus for connecting said trunk with a source of ringing current to operate said signal, a common source of operating and talking current connected in bridge of said trunk line, and subscriber controlled means for releasing said connection. 30
35. In a telephone system, a party line and a plurality of subscribers' stations in bridge thereof, a trunk line extending to an operator's position, means including an automatic switch having vertical and rotary motion controlled by a calling subscriber on said party line for connecting with said trunk line, ringing equipment associated with said trunk line for selectively signaling substations on said party line, and a common source of operating and talking current connected in bridge of said trunk line. 35
36. In a telephone system, a plurality of party lines, a plurality of subscribers' stations in bridge of each line, a trunk line extending to an operator's position, automatic switches, means for connecting one of said party lines with any one of said switches, each switch when seized by a calling line controllable over the two sides of such calling line in series for connecting with said trunk line, ringing equipment associated with said trunk line for selectively signaling substations on said party line, and a common source of operating and talking current connected in bridge of said trunk line. 40
37. In a telephone system, a line, a substation and a signal in bridge of said line, a trunk line extending to an operator's position, means including an automatic switch controllable by the subscriber at said substation for connecting with said trunk line, a ringing key apparatus for connecting said trunk with a source of ringing current to operate said signal, a signal to indicate to the operator when a call is received, a relay for controlling said signal connected in series with a battery across the talking conductors of said trunk line, said relay also controlled by said calling subscriber for releasing the connection. 45
38. In a telephone system, a party line and a plurality of subscribers' stations in

- bridge thereof, a trunk line extending to an operator's position, means including an automatic switch controlled by a calling subscriber on said party line for connecting with said trunk line, ringing equipment associated with said trunk line for selectively signaling substations on said party line, a signal to indicate to the operator when a call is received, a common source of operating and talking current connected in bridge of said trunk line, and means controlled by said calling subscriber for releasing said connection.
39. In a telephone system, a plurality of party lines, a plurality of subscribers' stations in bridge of each line, a trunk line extending to an operator's position, automatic switches, means for connecting any one of said party lines with any one of said switches, each switch when seized by a calling line controllable over the two sides of such calling line in series for connecting with said trunk line, ringing equipment associated with said trunk line for selectively signaling substations on said party line, a signal individual to the operator when a call is received, and a common source of operating and talking current connected in bridge of said trunk line.
40. In a telephone system, a line, a station and a signal in bridge of said line, a trunk line extending to an operator's position, means including an automatic switch controllable by the subscriber at said subscriber station for connecting with said trunk line, a ringing key apparatus for connecting said trunk with a source of ringing current to operate said signal, a signal to indicate to the operator when a call is received, a signal to indicate to the operator that the trunk is occupied, and a common source of operating and talking current connected in bridge of said trunk line.
41. In a telephone system, a party line and a plurality of subscribers' stations in bridge thereof, a trunk line extending to an operator's position, means including an automatic switch controlled by a calling subscriber on said party line for connecting with said trunk line, ringing equipment associated with said trunk line for selectively signaling substations on said party line, a signal to indicate to the operator when a call is received, a signal to indicate to the operator that the trunk is occupied, and a common source of operating and talking current connected in bridge of said trunk line.
42. In a telephone system, a plurality of party lines, a plurality of subscribers' stations in bridge of each line, a trunk line extending to an operator's position, automatic switches, means for connecting any one of said party lines with any one of said switches, each switch when seized by a calling line controllable over the two sides of such calling line in series for connecting with said trunk line, ringing equipment associated with said trunk line for selectively signaling substations on said party line, a signal to indicate to the operator when a call is received, a signal to indicate to the operator that the trunk is occupied, and a common source of operating and talking current connected in bridge of said trunk line.
43. In a telephone system, a party line and a plurality of substations in bridge thereof, a trunk line extending to an operator's position, means including a non-numerical switch responsive to the removal of the receiver at one of said substations and a directly controlled numerical switch accessible thereto for connecting said party line with said trunk line, sources of ringing current of different character, and means for separately connecting said sources with said trunk line to signal substations on said party line selectively.
44. In a telephone system, a party line and a plurality of substations in bridge thereof, a trunk line extending to an operator's position, means including a non-numerical switch responsive to the removal of the receiver at one of said substations and a directly controlled numerical switch accessible thereto for connecting said party line with said trunk line, sources of ringing current of different character, means for separately connecting said sources with said trunk line to signal substations on said party line selectively, means normally operative to release said switches when the subscriber replaces his receiver on the hook, and means whereby the operator can prevent such release after connection has been established with said trunk line.
45. In a telephone system, a party line and a plurality of substations in bridge thereof, a trunk line extending to an operator's position, means including a non-numerical switch responsive to the removal of the receiver at one of said substations and a directly controlled numerical switch accessible thereto for connecting said party line with said trunk line, sources of ringing current of different character, means for separately connecting said sources with said trunk line to signal substations on said party line selectively, and a common source of operating and talking current connected in bridge of said trunk line.
46. In a telephone system, a party line and a plurality of substations in bridge thereof, a trunk line extending to an operator's position, means including a non-numerical switch responsive to the removal of the receiver at one of said substations and a directly controlled numerical

switch accessible thereto for connecting said party line with said trunk line, sources of ringing current of different character, means for separately connecting said sources with 5 said trunk line to signal substations on said party line selectively, a signal to indicate to the operator when a call is received, a common source of operating and talking current connected in bridge of said trunk line, and 10 a signal to indicate to the operator that the trunk is occupied.

47. In an automatic telephone system, a plurality of party lines, a plurality of numerical selectors and connectors for connecting a calling subscriber on one line with a called subscriber on another line, a trunk line extending to an operator's position accessible to certain of said selectors whereby calling subscribers may connect with an operator, a source of talking current in bridge of said trunk line, and ringing equipment associated with said trunk for projecting ringing current back over a calling line connected thereto.

48. In an automatic telephone system, a plurality of party lines, a plurality of numerical selectors and connectors for connecting a calling subscriber on one line with a called subscriber on another line, a trunk line extending to an operator's position, means for making said trunk line accessible to certain of said selectors whereby calling subscribers may connect with an operator, a source of talking current in bridge of 35 said trunk line, and a selective ringing equipment associated with said trunk for projecting ringing current of different frequencies back over a calling line connected thereto.

49. In an automatic telephone system, a plurality of party lines, a plurality of numerical selectors and connectors for connecting a calling subscriber on one line with a called subscriber on another line, a trunk line extending to an operator's position, means for making said trunk line accessible to certain of said selectors whereby calling subscribers may connect with an operator, a source of talking current in bridge of said 50 trunk line, and a manually operated mechanism associated with said trunk, whereby the operator is enabled to project ringing current back over a calling line at the request of the calling subscriber.

50. In a telephone system, a party line and a plurality of substations in bridge thereof, a plurality of trunk lines at the exchange extending to an operator's position and a plurality of trunk lines at the 60 exchange extending to automatic switches, a selector switch, means for making said selector switch accessible to said party line, said selector switch controllable from a substation thereon for connecting with any one

of said trunk lines of either kind, and a 65 selective ringing equipment controlled by the operator for ringing back over any trunk line of the first kind when said party line is connected thereto to signal one of said substations. 70

51. In a telephone system, a plurality of lines, a plurality of substations in bridge of each line, a plurality of trunk lines at the exchange extending to an operator's position and a plurality of trunk lines at the 75 exchange extending to automatic switches for use in interconnecting said lines, a selector switch, means for making said selector switch accessible to a calling one of said lines and controllable from a substation 80 thereon for connecting with any one of said trunk lines of either kind, and a selective ringing equipment controlled by the operator for ringing back over any trunk line of the first kind to signal a called substation 85 on any line connected thereto.

52. In a telephone system, a party line, a selective ringing key apparatus, a trunk line leading to said apparatus, a switch controlled by a subscriber on said party line 90 for connecting said party line with said trunk line, a conductor extending through said switch to said apparatus, a subscriber controlled means for opening said conductor to release said switch. 95

53. In a telephone system, a party line, an operator's position, a trunk line leading to said operator's position, selective signaling apparatus associated with said trunk line, a progressively movable switch having 100 wipers to said switch for extending a connection from said party line to said trunk line over said wipers to enable one subscriber to call another on the same line, a circuit common to said switch and trunk 105 line passing through one of said wipers, and means controlled by the operator for opening said circuit to release said switch.

54. In a telephone system, a party line, a selective ringing key apparatus, a trunk 110 line leading to said apparatus, a selector having wipers and a bank, terminals for said trunk line in said bank, means for operating said switch to move said wipers to connect with said terminals, to enable one 115 party to call another on the same line, a circuit closed by the connection of said wiper with said bank, and means controlled by the calling subscriber for opening said circuit to release said switch. 120

55. In a telephone system, a party line, a selective ringing key apparatus, a trunk line leading to said apparatus, means for connecting said party line with said trunk line, to enable one party to call another on 125 the same line, said means including a switch individual to said party line, and subscriber controlled means for releasing said connec-

tion, and means for preventing the subscriber from releasing said connection.

56. In a telephone system, a plurality of party lines, a selective ringing key apparatus, a plurality of trunk lines leading to said apparatus, a numerical selector switch common to said party lines for extending a connection from one of said party lines to anyone of said trunk lines to enable one

party to call another on the same line, and 10 means controlled by the subscriber for releasing said numerical selector.

Signed by me at Chicago, Cook county, Illinois, this 29 day of June, 1910.

TALBOT G. MARTIN.
